UNITED STATES PATENT OFFICE.

ROBERT S. WITTMAYER, OF PORTLAND, OREGON.

INTERNAL-COMBUSTION ENGINE.

Application filed August 23, 1921. Serial No. 494,479.

To all whom it may concern:

Be it known that I, ROBERT S. WITTMAYER, a citizen of the United States, residing at Portland, in the county of Multnomah and State of Oregon, have invented certain new and useful Improvements in Internal-Combustion Engines, of which the following is a specification.

This invention relates to improvements in internal combustion engines and more particularly to that type in which the charge is compressed before admission into the explosion cylinder.

The general object of the present invention is to provide an engine of the pre-compression type simple in construction, efficient in operation, devoid of complicated operating parts, and capable of being adjusted to meet the conditions under which it is used.

One feature of the present invention resides in the construction and arrangement of the means provided for compressing the charge before delivery to the explosion cylinder, this means comprising charge compression cylinders which are cast integral with the heads of the explosion cylinder, the valves which control the supply of fuel to the explosion cylinder from the charge compression cylinders and the exhaust of the fired charge from the explosion cylinder being likewise housed within the heads of the said explosion cylinder, to thus simplify the construction and render it more compact and lighter in weight.

In engines of this type it has heretofore been customary to compress the charge through the reciprocation of pistons driven by a positive mechanical connection with the crank shaft of the engine and it has been impracticable to regulate or vary the degree of compression of the charge or the volume compressed with the result that an engine so constructed and designed for heavy duty work, will, if employed in performing lighter work, be very wasteful of fuel and difficult of control. It is therefore another important object of the present invention to provide for actuation of the charge compression pistons in such a manner that these pistons may be adapted to compress a charge to a degree suitable for heavy duty work or to a lesser degree for light duty work.

Another object of the invention is to provide for the independent actuation of the charge compression pistons so that their op-

eration may be more accurately timed and repairs more readily and economically effected; also, by providing for the independent operation of these pistons, should the operating means for either piston fail to function because of a temporary disarrangement of the parts, the engine will still be capable of operating to a satisfactory degree until the trouble can be located and preparations made for repairs.

A further object of the invention is to provide a novel arrangement and construction of inlet and exhaust valves as a result of which the admission of the charge and the exhaust of the products of combustion may be more accurately timed and controlled, and the explosion cylinder more thoroughly scavenged. Incidentally the invention contemplates regulation of the valves so as to suitably control the volume of fuel admitted to the explosion cylinder in accordance with the particular work to be done and thus effect an economy in fuel.

Another important object of the invention is to provide means whereby the explosion cylinder and its piston may be utilized as a brake.

A further object of the invention is to provide for lubrication of the piston of the explosion cylinder by a circulation of oil through the piston rod and within and about the piston head in a manner to also effect a cooling of these parts which has been found essential in engines of this type.

Other objects and advantages of the structure will be made clear in the specific description which is to follow.

In the accompanying drawings:

Figure 1 is a top plan view of an engine constructed in accordance with the present invention;

Figure 2 is a side elevation of the engine, one of the charge compression cylinders and some of its associated parts being shown in vertical section;

Figure 3 is a horizontal sectional view in detail taken substantially on the line 3-3 of Figure 2;

Figure 4 is a view partly in plan and partly in horizontal section illustrating the piston of the explosion cylinder;

Figure 5 is an end elevation of one of the cylinder heads;

Figure 6 is a vertical sectional view on the line 6-6 of Figure 5 looking in the direction indicated by the arrows:

2
Figure 7 is a side elevation of one of the exhaust valve cams;

Figure 8 is a rear elevation of the cam;

Figure 9 is a side elevation of one of the 6 inlet valve cams;

Figure 10 is a rear elevation thereof;

Figure 11 is a perspective view illustrating one of the slide valves and the parts associated therewith;

10 Figure 12 is a group perspective view illustrating the parts comprising one of the tappets for actuating the charge compression pistons.

In the drawings the principles of the invention are illustrated as embodied in a stationary engine but it will be understood that the invention is in no way limited to this particular embodiment and that the structure may be modified in any manner found 15 necessary in constructing the engine for installation in an automobile or in fact for use under any other conditions where an internal combustion engine may be employed.

25 The explosion cylinder of the engine is indicated in general by the numeral 1 and may be supported in any manner found suitable depending upon the conditions under which the engine is employed, and this cylinder comprises a cylindrical body 2 open at both of its ends and having fitted and removably-secured to its ends heads 3 and 4. Preferably the cylinder 2 is provided with a removable bushing or lining wall 5 which is 30 confined at its ends between the heads 3 and 4 when the heads are bolted in place but which may be removed for repair or replacement by removing either one or both of said heads. As the valves of the engine are contained within the heads 3 and 4, the bushing 5 is in the form of a cylindrical body imperforate throughout and may therefore be most economically produced. The piston which operates within the cylinder 1 is indicated 35 in general by the numeral 6 and the same has connected to it a piston rod 7 which operates through the head 4 and which is connected as at 8 with a cross head 9 supported for sliding movement upon a suitable base, 40 45 50 55 60 65 70 75 80 85 90 95 100 105 110 115 120 125

A pitman 11 is operatively connected with the cross head 9 and with a crank 12 forming a part of a crank shaft 13 mounted in suitable bearings 14 and 15. In order to accommodate the piston rod 7, the head 4 of the cylinder is provided with an opening 16 and with a collar extension 17 that surrounds the opening and which has its bore 18 gradually flared or increased in diameter in the direction of its outer end. Tapered or conical packing gaskets 19 are arranged within the bore of the collar extension 17 and are forced into place to form a fluid tight packing about the piston rod 7, by means of a packing nut 20 which is exteriorly threaded onto the said collar exten-

sion. The construction of the piston head 6 and its rod 7 to provide for lubrication and cooling of these parts will presently be more specifically described. The cylinder 2 is provided with a water jacket or outer wall 21 forming a water space 22 extending substantially continuously about its circumference, and the heads 3 and 4 of the said cylinder are provided respectively with water spaces 23 and 24 placed in communication 75 with the cylinder water space by way of ports 25 and 26 respectively, means being thus provided for cooling the cylinder walls and heads.

The cylinder heads 3 and 4 are provided 80 with intake ports 27 and 28 respectively and with exhaust ports 29 and 30 respectively, these ports being in communication with the respective ends of the explosion cylinder 1 as clearly shown in Figure 3 of the drawings. The numerals 31 and 32 indicate charge compression cylinders which are respectively cast integral with the heads 3 and 4 and placed in communication with the explosion cylinder 1 respectively by way 90 of the ports 27 and 28.

The exhaust manifold of the engine is indicated in general by the numeral 33 and the same is provided with branches 34 and 35 respectively placed in communication with 95 the exhaust ports 29 and 30. The exhaust ports 29 and 30 are respectively controlled by slide valves 36 and 37 mounted for reciprocation in the heads 3 and 4 respectively and each provided with a transverse relatively narrow port 38 adapted to be brought into and out of communication with the respective ports 29 and 30 in the reciprocation of the valves. One of these valves as for example the valve 36 is clearly illustrated in 100 Figure 11 of the drawings and each of the valves is provided at its lower end with a stem 39 which projects downwardly and has pin and slot connection as at 40 with a rock arm 41 fixed upon one end of a short shaft 105 110 115 120 125 42 mounted beneath the respective head 3 or 4 as the case may be. A crank arm 43 is carried by the other end of shaft 42, and connecting rods 44 are pivotally connected to the upper ends of the arms 43 and are led rearwardly and connected to the upper ends of similar crank arms 45 mounted upon short shafts 46 located one side of the support 10 for the cross head 9. Other rock arms 47 upstand from the shafts 46, and rods 48 are connected thereto and work through suitable guides 49. The rear ends of the rods 48 carry rollers 50 which are held in contact with the peripheries of cams 51 fixed upon the crank shaft 13, the rods being held with their rollers in engagement with the cams through the medium of springs 52 which are fitted onto the rods and bear between the guides 49 and collars 53 which are fixed upon the said rods. One 130

of the cams is illustrated in Figure 7 of the drawings and each is preferably formed in two sections one indicated by the numeral 54 and the other by the numeral 55, these sections being provided with bosses or ears 56 whereby they may be bolted together about the crank shaft 13 and being also provided, if desired, with threaded openings 57 so that set screws may be fitted through the sections 54 and 55 to bind against the shaft and thus hold the cams securely in positions of adjustment. One section as for example the section 54 of each cam is provided with a cam nose 58 having relatively abrupt ends 59 the advancing one of which is adapted to ride against the respective roller 50 and impart a sudden shifting motion to the respective rod 48, and through the medium of the intermediate connections above described, to immediately move the corresponding exhaust valve 36 to open position, the valve being maintained in this position so long as the nose 58 of the respective cam is riding against the respective roller 50. Of course as soon as the opposite or following end of the cam nose rides beneath the respective roller, the spring 52 will return the respective rod 48 to its normal position and, through the intermediate connections described, immediately move the respective exhaust valve 36 to closed position.

The supply of fuel through the intake ports 27 and 28 is controlled by intake slide valves indicated respectively by the numerals 60 and 61 each of which is provided with a transverse relatively narrow intake passage or port 62. The valves 60 and 61 are furthermore of the same general construction as the valves 36 and 37 so that a specific description thereof is deemed unnecessary. The lower ends of the stems of the valves 60 and 61 are connected by pin and slot connection 63 to rock arms 64 which are fixed upon shafts 65 suitably supported beside the cylinder of the engine. Crank arms 66 up-stand from the shafts 65, and rods 67 are connected as at 68 to these arms and extend rearwardly and are provided with pivot bolts 69 at their opposite ends which are adjustably engaged through slots 70 formed in rocking links 71 which project upwardly from shafts 72 mounted parallel to the crank shaft of the engine. Crank arms 73 also up-stand from the shafts 72, and rods 74 are pivotally connected as at 75 with the said arms 73 and are provided at their ends with rollers 76 which are yieldably held in contact with the peripheries of cams 77 fixed upon the crank shaft 13, springs 78 being fitted onto the rods 74 and bearing between collars 79 which are fixed upon the said rods, and suitable guides 80 which support the rods for reciprocation. One of the cams 77 is clearly illustrated in Figures 9 and 10 of the drawings and is of the same general construction as the cams 51 except that the nose of the cam 77, which is indicated by the numeral 81, merges at its working edge at one end with the peripheral surface of the cam as at 82 and is gradually increased in height 70 from this point to its opposite end which is indicated by the numeral 83 and which is of abrupt formation as shown in Figure 9. It will now be evident that as the noses 81 of the cams 77 ride against the respective rollers 76, the respective rods 74 will be shifted in a manner to effect opening of the respective intake valves and an immediate closing of the valves as the rollers ride over the abrupt ends 83 of the said noses and the springs 78 are permitted to act.

Charge compression pistons 84 and 85 reciprocate respectively in the charge compression cylinders 31 and 32, and each of these pistons comprises a head 86 having a rod 87 extending axially from its under side and fitting through a stuffing box 88 in the closed lower end 89 of the respective cylinder. A cylindrical plate 90 is fitted onto the lower end of each piston rod 87 and 90 adapted to be adjusted longitudinally of the rod through the adjustment of a nut 91 threaded onto the said end of the rod, this nut being preferably in turn held in adjustment by means of a jam nut 92. A compression spring 93 is disposed about the rod 87 of each charge compression piston and bears at its lower end upon the respective plate 90 and at its upper end against the closed lower end 89 of the respective charge compression cylinder and at this point it will be understood that when the piston of either cylinder is moved upwardly and then released, the respective spring 93 will first be compressed and will then be permitted to expand, in the latter instance forcing the piston on its downward stroke.

The upward movement of the charge compression pistons serves to draw into the respective cylinders the charge to be compressed and delivered to the explosion cylinder 1, and with this end in view an intake manifold 94 is cast upon one side of the cylinder 1 and is placed in communication at its ends with intake ports 95 and 96 provided respectively in the sides of the charge compression cylinders 31 and 32 at the lower ends thereof. Check valves of any suitable construction indicated by the numerals 97 and 98 are arranged in the opposite ends of the intake manifold 94 and permit the delivery of the charge from the manifold to the cylinders 31 and 32 respectively and prevent return of the charge to the said intake manifold, the check valves 110 being preferably of the spring closed type and also being preferably removably fitted into place so that they may be repaired if occasion arises. The intake manifold 94 is provided between its ends with an intake 130

which in practice will be placed in communication with any suitable carbureting device.

In addition to the rods 87, the charge compression pistons 84 and 85 are provided with stems 100 which extend axially from their upper sides and are preferably guided by spiders 101 arranged within the upper ends of the charge compression cylinders, these ends of the cylinders being open to the atmosphere. A tappet head 102 is fixed upon the upper end of each stem 100 and is provided with oppositely beveled upper surfaces 103 and with a squared or shouldered lower end 104 whereby the tappet arms which will now be described may coact therewith. The tappet arms are indicated in general one by the numeral 105 and the other by the numeral 106 and are respectively associated with the stems of the pistons 84 and 85. Each of these tappet arms comprises a collar 107 fixed in any suitable manner upon a respective one of a pair of rock shafts 108 mounted above the explosion cylinder, and each collar 107 is provided with spaced apertured ears 109 for the passage of a pivot pin 110 which fits also through interfitting pivot ears 111 formed at the inner ends of a pair of members 112 comprising the respective arm 105 or 106 as the case may be. A bolt 113 is fitted through aligned openings 114 formed in the members 112 of each arm and has fitted upon it a spring 115 which bears against the outer side of one of the members 112 and serves to yieldably urge the members toward each other, the members being capable however of pivotal movement against the tension of the spring 115 in a direction to effect their relative separation. Forwardly beyond the connecting bolt 113, the opposing sides of the members 112 are beveled as indicated by the numeral 116. It will now be understood that when the shafts 108 are rocked in one direction, the respective arms 105 or 106 as the case may be will be swung downwardly until the beveled surfaces 116 of their members 112 ride against the beveled surfaces 103 of the respective tappet head 102 whereupon, in further downward swinging movement of the said arm, the members 112 will be relatively separated against the tension of the spring 115 until their beveled portions ride past the lower end of the said tappet head 102 whereupon the spring 115 will act immediately to swing the members 112 toward each other so that their upper edges will engage beneath the lower end 104 of the tappet head 102 at the opposite sides of the stem 100. The said upper edges of the members 112 are curved or rounded in the direction of the free outer ends of the members as indicated by the numeral 117 so that these edges will act as cams, when the respective shaft 108 is rocked in a reverse di-

rection thereby exerting an upward pressure against the respective tappet head 102 and imparting an upward stroke to the respective charge compression piston 84. When the tappet arms reach a predetermined limit of their upward movement, they sweep from engagement with the respective tappet heads 102 thus releasing the respective charge compression pistons for their downward stroke under the influence of the respective springs 93.

In order that rocking motion may be imparted to the shafts 108 in timed relation to the functioning of the other operating parts of the engine, crank arms 118 are fixed upon the said shafts 108 and are provided with wrist pins 119. Connecting rods 120 are provided with open sided bearings 121 engageable over and resting by gravity in operative connection with the wrist pins 119 and capable therefore of being swung upwardly to become disengaged from the said pins. At their opposite ends the said rods 120 are connected to cranks or eccentrics 122 upon the shaft 13. It will now be evident that so long as the bearings 121 of the connecting rods 120 are in operative engagement with the wrist pins 119 and the crank shaft 13 is rotating, the charge compression pistons 84 and 85 will be operated but in order that this operation may be discontinued so as to render the said pistons 84 and 85 inactive and thus adapt the piston 6 to serve as a brake through compression of air in the opposite ends of the explosion cylinder 1, means is provided for swinging both of the rods 120 in an upward direction to inactive position and free from connection with the wrist pins 119. This means may vary in its structural details in accordance with the varying conditions under which the engine will be used, but is illustrated in the drawings as comprising a rock shaft 123 mounted upon any suitable fixed support and provided with a cranked portion 124 extending transversely beneath the rods 120. A manually operable lever 125 is also fixed upon the shaft 123 and is provided with a pawl 126 for coaction with a segmental rack 127, the lever 125 being adapted to be swung in a manner to so rock the shaft 123 as to cause the cranked portion 124 thereof to ride upwardly beneath the connecting rods 120 and elevate the rods in the manner stated. Of course the rods may be returned to lowered or active position by a reverse adjustment of the lever 125 when it is again desired to resume operation of the charge compression pistons 84 and 85.

In order that the piston head 6 and rod 7 may be cooled and the head 6 lubricated, the said head 6 is formed interiorly with lubricant chambers 128 and 129 separated by a partition wall 130 located between the

front and rear ends of the said head, the head being formed exteriorly with a circumferentially extending lubricant channel 131 located substantially in the plane of the partition wall 130 and being provided at the front and rear of the channel with piston rings 132. Ports 133 and 134 establish communication between the channel 131 and the lubricant chambers 128 and 129 respectively, and the head 6 is formed with a concentrically located core 135 into which the end of the rod 7 is fitted, the wall of this core being threaded for a portion of its length as at 136 to receive the reduced threaded extremity 137 of the said rod 7 and being provided inwardly of its threaded portion with circumferentially extending channels 138 and 139. Ports 140 and 141 are formed in the wall of the core 135 and establish communication respectively between the channel 138 and lubricant chamber 128 and the channel 139 and lubricant chamber 129. The piston rod 7 is formed with longitudinally extending lubricant passages or ducts 142 and 143 which at the head end of the rod communicate respectively with the channels 138 and 139 preferably at points opposite the respective ports 140 and 141. Flexible tubes 144 and 145 are introduced into the opposite end of the rod 7 and are placed respectively in communication with the passages 142 and 143. In practice, oil from any suitable source of supply under pressure will be forced through one of the tubes as for example the tube 144 and, after flowing through the passage 142, will pass by way of the channel 138 and port 140 into the lubricant chamber 128 in the piston head 6. Being under pressure the oil will then be caused to flow from this chamber to the port 133 and into the channel 131 where a suitable quantity thereof will be taken up by the surfaces of the piston head and lining wall 5 of the cylinder 1, the greater volume however being delivered through the port 134 into the chamber 129 and from this chamber through the port 141 into the passage 143, the oil being conducted from the system through the tube 145.

By setting the eccentrics and cams upon the crank shaft 13, the operation of the intake and exhaust valves and the operation of the charge compression pistons is so timed as to bring about a cycle of operation as follows:

In a preceding cycle of operation the piston 6 has moved from the dotted line position shown in Figure 3 to the full line position and during this movement the intake valve 61 has idled in closed position due to the engagement of the respective roller 76 against the low portion of the respective cam 77. However the exhaust valve 37 has been moved to open position by the riding

of the nose of the respective cam 51 against the respective roller 50, and the said exhaust valve 37 remains in this position until substantially the moment when the piston 6 reaches the limit of its stroke in the direction of the full line position illustrated at which moment the nose of the respective cam 51 will ride out of engagement with the respective roller 50 and the valve 37 will be immediately closed. At the moment of closing however the scavenging of the respective end of the cylinder has been completed so that there is no appreciable residue of the exhaust gases in this end of the cylinder. The valve 37 will then idle in closed position until the piston 6 has been again driven to its dotted line position in Figure 3 and starts on its return stroke to its full line position. While the piston is traveling from the dotted to the full line position, the charge compression piston 85 is elevated against the tension of the respective spring 93 through the upward swinging movement of the tappet arm 106 and the coaction of the upper side of this arm with the tappet head 102 upon the stem of the said piston 85. The upward movement of this piston serves to draw into the cylinder 32 a charge of explosive mixture which is trapped by the check valve 98. As soon as the arm 106 disengages from the respective tappet head 102, the spring 93 acts immediately to force the charge compression piston 85 on its downward stroke and the charge will be compressed by the piston to a degree in ratio to the force exerted by the spring 93 in expanding and such force may be varied or regulated through adjustment of the nuts 91 and 92 and the plate 90 as previously explained. At the moment the exhaust valve 37 has practically reached its closed position and the end of the cylinder has been completely scavenged, the nose of the respective cam 77 riding against the respective roller 76 will open the intake valve 61, the movement of this valve to open position and the inrush of the compressed charge through the port 62 of the valve and into the end of the explosion cylinder 1 taking place during the final closing of the exhaust valve 37 and continuing until the moment when the piston 6 has reached the limit of its stroke in the direction of its full line position. As the abrupt end 83 of the nose of the cam 77 rides past the roller 76, the valve 61 will be instantly moved to closed position, and at this moment the charge is fired. The piston is therefore impelled, by the explosion of the charge, from the full line position shown in Figure 3 toward the dotted line position and as it so moves, the valves 36 and 60 will be actuated in precisely the same timed relation as that above recited in connection with the valves 37 and 61, the operation of the charge compression piston 85

86 being likewise in the same timed relation as previously explained in connection with the piston 85. It will be evident that the degree which the charge is compressed in 5 the charge compression cylinders may be varied or regulated by adjusting the plates 90 against which the lower ends of the springs 93 bear, and it is further evident that should the working conditions be such 10 that all of the compressed charge is not delivered from either compression cylinder, the remainder of the charge will remain under compression and will be reserved until the corresponding piston is again moved on 15 its up-stroke to take in a fresh volume of explosive mixture. By adjusting the pivot bolts 69 in the links 71, the throw of the rods 67 and consequently the throw of the valves 60 and 61 may be regulated so as to 20 provide for the admission of a greater or lesser volume of the explosive mixture to adapt the engine for heavy or light duty work.

Having thus described the invention what 25 is claimed as new is:

1. In an internal combustion engine of the precompression type, an explosion cylinder, and means for compressing a gaseous charge prior to delivery to the said cylinder comprising a charge compression cylinder having a charge intake, and a part in communication with the explosion chamber, a piston working in the charge compression cylinder, means operable to positively actuate the piston on its intake stroke and completely release the piston at the end of said stroke, and tension means for actuating the piston on its compression stroke.

2. In an internal combustion engine of the precompression type, an explosion cylinder, and means for compressing a gaseous charge prior to delivery to the said cylinder comprising a charge compression cylinder having a charge intake, and a port in communication with the explosion cylinder, a piston working in the charge compression cylinder, tension means continuously urging the piston in the direction of its compression stroke, and means operable to positively move the piston on its intake stroke and completely release the same for actuation by the first mentioned means at the end of said stroke.

3. In an internal combustion engine of the precompression type, an explosion cylinder, and means for compressing a gaseous charge prior to delivery to the said cylinder comprising a charge compression cylinder having a charge intake, and a port in communication with the explosion cylinder, a piston working in the charge compression cylinder and having a rod extending exteriorly thereof, a compression spring acting upon the rod to continuously urge the piston in the direction of its compression

stroke, and means operating to move the piston on its intake stroke and instantly disengage from and release the same for actuation by the said spring at the end of said stroke.

4. In an internal combustion engine of the precompression type, an explosion cylinder, and means for compressing a gaseous charge prior to delivery to the said cylinder comprising a charge compression cylinder having a charge intake and a port in communication with the explosion cylinder, a piston working in the charge compression cylinder, tension means urging the piston in the direction of its compression stroke, means operating to move the piston on its intake stroke and release the same for actuation by the tension means, and means operable to adjust the tension of the said tension means whereby to vary the force exerted by it against the piston.

5. In an internal combustion engine of the precompression type, an explosion cylinder, and means for compressing a gaseous charge prior to delivery to the said cylinder comprising a charge compression cylinder having a charge intake and a port in communication with the explosion cylinder, a piston working in the charge compression cylinder and having a rod extending exteriorly thereof, an abutment member adjustably mounted upon the rod, a compression spring acting against the abutment member to urge the piston in the direction of its compression stroke, and means operating to move the piston on its intake stroke and instantly disengage from and release the same for actuation by the spring at the end of said stroke.

6. In an internal combustion engine of the precompression type, an explosion cylinder, and means for compressing a gaseous charge prior to delivery to the said cylinder comprising a charge compression cylinder having a charge intake and a port in communication with the explosion cylinder, a piston working in the charge compression cylinder, tension means urging the piston in the direction of its compression stroke, the piston having a stem extending exteriorly of the cylinder, a tappet head upon the stem, and a tappet member operating in connection with the said tappet head to successively exert force upon the stem to move the piston on its intake stroke and then disengage to permit actuation of the piston by the tension means on its compression stroke.

7. In an internal combustion engine of the precompression type, an explosion cylinder, and means for compressing a gaseous charge prior to delivery to the said cylinder comprising a charge compression cylinder having a charge intake and a port in communication with the explosion cyl-

inder, a piston working in the charge compression cylinder, means urging the said piston in the direction of its compression stroke, the piston having a stem extending 5 exteriorly of the cylinder, a tappet head upon the stem, and means coacting with the tappet head to move the piston on its intake stroke, said means comprising an oscillatory tappet arm including pivotally 10 supported relatively separable members, and means yieldably resisting separation of the members, the members, in the movement of the arm in one direction, being arranged to ride over and past the tappet head and 15 engage behind the same, and in the movement of the arm in the other direction being arranged to act against the head to exert force upon the said stem and finally disengage from the head to release the piston 20 for actuation by the said urging means.

8. In an internal combustion engine of the precompression type, an explosion cylinder, charge compression cylinders each in communication with a respective end of the explosion cylinder and each having a charge intake, a piston working in each charge compression cylinder, a piston operating in the explosion cylinder, a shaft driven from the said piston, means urging the charge 25 compression pistons in the direction of their compression stroke, and means for actuating the charge compression pistons on their intake strokes comprising rock shafts, tappet arms carried by the shafts, stems extending 30 from the pistons, tappet elements upon the stems engageable by the tappet arms when the arms are swung in one direction whereby to effect movement of the respective piston on its intake stroke and then disengage to 35 permit actuation of the piston by the urging means, crank elements upon the said rock shafts, connecting rods having crank connection with the first mentioned shaft and separably engaged with the crank elements upon the rock shafts, and means 40 operable to disengage the connecting rods from the said crank elements whereby to render the tappet arms inactive.

9. In an internal combustion engine of the precompression type, an explosion cylinder, a head upon one end thereof having an exhaust port and an intake port, a slide valve controlling the exhaust port, a slide valve controlling the intake port, means 45 operating the said valves in timed relation, a charge compression cylinder upon the head in communication with the intake port, a piston working in the said charge compression cylinder, means for actuating the piston, an intake manifold upon the explosion cylinder in communication with the charge compression cylinder, and a check valve within the intake manifold in position to be exposed upon removal of the cylinder head.

In testimony whereof I affix my signature.
ROBERT S. WITTMIEIER. [L. s.]

precompression type, an explosion cylinder, charge compression cylinders each in communication with a respective end of the explosion cylinder and each having a charge intake, a piston working in each charge compression cylinder, a piston operating in the explosion cylinder, a shaft driven from the said piston, means urging the charge compression pistons in the direction of their compression stroke, and means for actuating the charge compression pistons on their intake strokes comprising rock shafts, tappet arms carried by the shafts, stems extending 55 from the pistons, tappet elements upon the stems engageable by the tappet arms when the arms are swung in one direction whereby to effect movement of the respective piston on its intake stroke and then disengage to 60 permit actuation of the piston by the urging means, crank elements upon the said rock shafts, connecting rods having crank connection with the first mentioned shaft and separably engaged with the crank elements upon the rock shafts, and means 65 operable to disengage the connecting rods from the said crank elements whereby to render the tappet arms inactive.

10. In an internal combustion engine of the precompression type, an explosion cylinder, a head upon one end thereof having an exhaust port and an intake port, a slide valve controlling the exhaust port, a slide valve controlling the intake port, means 70 operating the said valves in timed relation, a charge compression cylinder upon the head in communication with the intake port, a piston working in the said charge compression cylinder, means for actuating the piston, an intake manifold upon the explosion cylinder in communication with the charge compression cylinder, and a check valve within the intake manifold in position to be exposed upon removal of the cylinder head.
